UNITED STATES PATENT OFFICE.

MAX LAUTERBACH, OF SEDALIA, MISSOURI.

HARNESS-SADDLE.

No. 860,812.

Specification of Letters Patent.

Patented July 23, 1907.

Application filed June 30, 1906. Serial No. 324,248.

To all whom it may concern:

Be it known that I, MAX LAUTERBACH, a citizen of the United States, residing at Sedalia, in the county of Pettis and State of Missouri, have invented a new and 5 useful Harness-Saddle, of which the following is a specification.

This invention relates to improvements in harness saddles, and has for its object to improve and simplify the construction and increase the strength and durability of devices of this character.

With these and other objects in view, which will appear as the nature of the invention is better understood, the invention consists in certain novel features of construction as hereafter fully described and claimed.

15 In the accompanying drawings forming a part of this specification and in which corresponding parts are denoted by like designating characters, is illustrated the preferred form of the embodiment of the invention capable of carrying the same into practical operation, 20 it being understood that various changes in the form, proportion, and minor details of construction may be resorted to without departing from the principle or sacrificing any of the advantages of this invention within the scope of the appended claims.

25 In the drawings:—Figure 1 is a perspective view of the main body or “tree” portion of the improved device; Fig. 2 is a perspective view, inverted, of the saddle seat portion, detached; Fig. 3 is a perspective view of the check rein hook, detached; Fig. 4 is a view of the 30 clamp screw; Fig. 5 is a sectional view longitudinally of the central portion of the improved device; Fig. 6 is a section on the line 6—6 of Fig. 5. Fig. 7 is a sectional detail illustrating a modification in the construction.

The improved device comprises a body or base 10 of 35 metal, preferably of malleable iron or cast steel, said base being provided with inclined extended sides 11—12, having apertures 13—14 to receive the terret supporting bolts. A socket 15 is formed in the upper face of the base 10 and said socket is provided with a recess 40 16 in its bottom, as shown more clearly in Fig. 1.

The upper face of the base portion 10 is cut away at the opposite sides of the socket 15 to form shoulders 17—18, and the rear part of the base is extended into a loop 19 adapted to receive the back strap of the harness, not shown.

45 The saddle seat portion of the device is represented in Figs. 2, 3 and 5, and consists of the body 20 extended rearwardly and laterally at 21 in the usual form and with a depending central portion or lug 22 relatively thick and a depending lug 23 relatively thin, the thicker lug having a stud or pin 24 extending therefrom and the thinner lug having a threaded recess 25, the stud adapted to enter the recess 16 in the socket 15 and the threaded aperture being adapted to receive a

clamp screw 26 operating through an aperture 27 in the 55 base portion 10 of the “tree”.

The check rein hook is represented at 28, and is provided with a laterally extending base 29 corresponding to and adapted to be seated in the socket 15 of the base 10, said base being provided with an aperture 30 through 60 which the stud 24 passes on its way to its seat in the recess 16.

The outer or side edges of the base portion 20 of the saddle seat are depressed slightly and overhang the base portion 10 of the “tree”, as represented at 31—32 65 in Fig. 6, to form dovetailed recesses between the lugs 22—23 and the portions 10 and 20 of the device, to assist in holding the parts together.

70 The leather “skirts” of the saddle portion of the harness are indicated in part at 33—34 and the sheet metal jockey plate at 35 and bearing over the skirts and also around the lug 22 and beneath the lug 23 and through 75 which the clamp screw 26 operates. The jockey plate thus extends beneath the overhanging portions 31—32, and the leather cover of the jockey plate, indicated at 75 36, also extends beneath the overhangs and is compressed thereby.

By this simple arrangement it is obvious that all the parts are firmly clamped together and held in position by the one single clamp bolt 26, and require no other 80 securing means.

The device is simple in construction, can be inexpensively manufactured, and applied to any of the various forms and sizes of harness manufactured.

When employed in connection with harness in which 85 “jockey” plates are not employed, the member 36 bears directly upon the tree 10 as shown in Fig. 7.

What is claimed is:—

A harness saddle tree including a body portion having oppositely disposed inclined arms and provided with a transverse enlargement at the juncture of said arms and projecting above the upper surface of the body portion to form oppositely disposed shoulders, one end of said enlargement being extended laterally beyond the adjacent longitudinal edge of the body portion to form a terminal loop, the opposite end thereof being disposed flush with the adjacent edge of said body portion and provided with a rectangular recess opening through said edge, there being an aperture formed in the enlargement at said recess, a check rein hook seated in said recess and provided with an aperture adapted to register with the aperture in the wall of the recess, a saddle seat engaging the base of the check rein hook and provided with a depending stud adapted to enter the apertures in the hook and wall of the recess, respectively, and a fastening device for clamping the saddle seat in position on the enlargement.

In testimony that I claim the foregoing as my own, I have hereto affixed my signature in the presence of two witnesses.

MAX LAUTERBACH.
